UNITED STATES PATENT OFFICE.

THOMAS W. MCNEILL AND IRA J. BABCOCK, OF CHICAGO, ILLINOIS.

SMOKE-INDICATOR.

1,103,603.

Specification of Letters Patent. Patented July 14, 1914.

Application filed March 17, 1913. Serial No. 754,937.

To all whom it may concern:

Be it known that we, THOMAS W. MCNEILL and IRA J. BABCOCK, citizens of the United States, residing at Chicago, in the county of Cook and State of Illinois, have invented certain new and useful Improvements in Smoke-Indicators, of which the following is a specification.

Our invention relates to improvements in smoke indicators and more particularly to apparatus for association with a smoke education passage, as the breeching, stack, or other duct through which the products of combustion from a fuel burner pass, to enable its user to observe the relative transparency or opacity existent within said passage.

One of the objects of our invention is to provide an apparatus operating according to the principles embodied in the construction of our prior patent No. 1,012,403, dated December 19, 1911, for smoke-indicators, but having certain advantages over our previous invention in that its use in dusty atmospheres does not result in a disturbing deposit upon the transparent closure and the reflecting mirrors, and in other matters which will become more apparent from a consideration of the following description when taken in conjunction with the drawing, 30 wherein—

Figure 1 is a sectional view of a breeching, or like smoke-educting passageway or flue, having applied thereto part of the apparatus; and Fig. 2 is a sectional view of another part of the apparatus which in use is adapted to be located at some distance removed from but in alinement with the apparatus shown in Fig. 1.

In the showing illustrated in the drawing, 40 5 indicates the breeching, exemplifying any suitable flue or other passageway leading from a fuel burner, and 6—6' indicate perforations in the walls of such breeching, the perforations being diametrically opposite 45 and each having associated therewith a tube, indicated respectively at 7 and 8. Each of said tubes 7 and 8 is relatively short and has at one end a flange 9 by which it may be secured to the breeching. For coöperation 50 with the free otherwise open end of each said relatively short tubes 7 and 8 I provide suitable regulable-vent caps, one whereof carries an illuminating means and the other whereof is closed by a plate of glass. Specifically, in the particular construction shown 55 for purposes of disclosure, 10 indicates a

thimble adapted to be inserted within the free end of tube 7, said thimble having a bead at 11 for coaction with the free edge of said tube and being outwardly bent, as 60 at 13, from a point somewhat beyond the bead 11, the thimble between said bead and outwardly bent portion having a series of perforations 14. For coaction with said perforated portion, we provide a similarly perforated, rotatably shiftable, ring, so that the thimble may be opened to provide a series of vents into the tube 7, may be closed to prevent passage of air into the thimble, or may be partially opened to admit regulable quantities of air.

Hinged as at 16 upon the outwardly bent portion 13 of the thimble 10, we provide a reflector 17, a spring clip 18 being preferably provided on the tube portion 13 for 75 engagement over the edge of the reflector to retain it tightly in place as a closure upon the end of the thimble. Within the reflector we mount a suitable means for producing a light, such means preferably taking the form of an electric incandescent lamp 19, current to which may be supplied by wires extending through the end 20 of the reflector.

It will be seen that the construction is operable to completely close the thimble or to 85 open the same by rotation of the vented ring 15.

Upon the tube 8 we provide a thimble, generally similar in construction, but having, in lieu of the reflector and lamp, a glass plate 21'. In other respects the construction of the closure for tube 8 resembles that for tube 7, heretofore described, having the same sort of perforations, coacting perforated ring, hinge clip, etc., so that it will be 95 unnecessary for us to describe the same in detail.

In this construction, the light from lamp 19 passes through tube 7, across the smoke flue 5, through tube 8, and the glass plate 21' 100 which is carried by the thimble for said tube 8, so that it may be observed and the density of smoke passing through the flue thereby detected. It usually happens, however, that the observations are desired to be taken 105 at points relatively remote from the flue to which the thimbles described have been applied, and that such point of observation is not in direct alinement with the tubes 7 and 8. Our invention therefore contemplates, in conjunction with the apparatus already described, a deflector mechanism 110

such as shown in Fig. 2. This mechanism, as illustratively shown in the drawing, comprises a triangularly shaped casing member 1 having one of its sides open, as indicated at 26, over the opening of which may be hinged a reflecting mirror 27, the hinge being indicated at 28 and a closure retaining clip, similar to clip 18 for the lamp-reflector, being indicated at 29. The other two sides of said triangular casing each provide a sleeve, indicated respectively at 30 and 31, over one of which a relatively short tube 32 may be inserted, said tube having free edges as at 33. When the reading may be taken without further deflection of the light, the other sleeve may be formed, as at 34, to provide a hinge and at the diametrically opposite side carries a clip for engagement of a cylinder 23', a translucent screen being provided, as indicated on the drawing, to receive the ray of light and thereby facilitate the reading. When, however, more than one turn of the light ray is required in order to bring it to the point of observation, intermediate deflectors may be used, which omit the translucent screen.

In this installation of devices as above described, as many of the mirror-carrying casings 25 may be used as will be necessary to deflect the ray of light from the lamp 19 to the desired point of observation, and each of said casings may be placed as far from the preceding one, or from the flue to which the tube 8 is applied, as may be convenient. In our previous disclosure we have shown a continuous tubing leading from one to the other of the turns required in the path of the light, but we have found from practical experience that, in the passage of dust-laden air through the tubing and past the mirrors 27, a more or less opaque deposit soon accumulates upon said mirrors so that the indication at the end of the tubing is not accurate. The present invention will be seen to avoid this objection which is present in our previous apparatus.

In the use of the apparatus, set up as above stated, it will be apparent that some smoke may pass up into the tubes 7 and 8 due to the eddy effect produced thereby, so that the light from lamp 19 would be deadened to greater extent than it should be from passing through only the smoke in the flue. Therefore the rings 15 may be turned to open the vents, and a draft will be caused to flow from the exterior air through said vents 14, through the tubes 7 and 8 respectively, and into the flue 5, so that the tubes 7 and 8 will be filled with relatively clear air from the exterior and the reading obtained by means of the ray of light issuing from the tube 8 will be accurate. It will be noted that in this passage of air through the tubes it is at no time caused to strike against the glass plate carried by said tube 8, so

that the tendency of said plate to become covered with dust is minimized and the accuracy of the system increased. In similar manner, there is no tendency to smut the mirror 27 since, in our present apparatus, there is no constant passage of dust-laden air therewith. We have therefore found that the present apparatus remains accurate in its indications through long periods of time, requiring less attention than our earlier apparatus and at the same time eliminating the long connecting tubing with reduced cost and less encumbrance to the room across which the ray of light passes.

Other advantages will become apparent.

While we have herein described and shown an embodiment of our invention, it will be apparent that changes may be made in the non-essential details, without departing from the spirit of the invention and within the scope of the appended claims.

What we claim is:

1. In an apparatus of the character described, the combination, with a smoke flue, of two relatively short, diametrically opposite, alining tubes associated with the flue, one of said tubes having associated therewith a source of light and the other having its end closed by a glass plate, and a light-deflecting structure comprising a casing, a mirror in said casing, short free-ended tubes extending from said casing at such an angle that a ray of light passing through one said tube and deflected by the mirror will pass through the other tube, and a translucent plate carried by one of said tubes, whereby said mirror-carrying casing may be placed with one of its tubes in alinement with the plate-carrying tube of the flue, but spaced therefrom any desired distance, for purposes described.

2. An apparatus of the character described, for use with a smoke flue, comprising a plurality of separated devices, each whereof provides a short free ended tube for disposition in alinement with a like tube of another of said devices, a source of light associated with the smoke flue for projecting a ray of light across the flue through one of said tubes, across the intervening unoccupied space between said tube and the alining tube of another of said devices, into said alining tube; a deflecting mirror associated with that device which carries said alining tube; and a second short free-ended tube associated with said last mentioned device for passage therethrough of said deflected ray of light.

3. An apparatus of the character described, for use with a smoke flue, comprising a plurality of separated devices, each whereof provides a short free-ended tube for disposition in alinement with a like tube of another of said devices, a source of light associated with the smoke flue for projecting

a ray of light across the flue through one of said tubes, across the intervening unoccupied space between said tubes and the alining tube of the other said device, and into said 5 alining tube; a deflecting mirror associated with that device which carries said alining tube; and a second short free-ended tube, associated with said last-mentioned device, for passage therethrough of said deflected 10 ray of light, and a plate in one of the tubes

of said mirror-carrying device to prevent currents of air therethrough for purposes described.

In testimony whereof we hereunto set our hands.

THOMAS W. MCNEILL.
IRA J. BABCOCK.
